UNITED STATES PATENT OFFICE.

CHESTER H. THORDARSON, OF CHICAGO, ILLINOIS.

COIL STRUCTURE FOR TRANSFORMERS AND THE LIKE.

1,255,948.

Specification of Letters Patent.

Patented Feb. 12, 1918.

Original application filed July 10, 1915, Serial No. 39,044. Divided and this application filed April 23, 1917.
Serial No. 163,866.

To all whom it may concern:

Be it known that I, CHESTER H. THORDARSON, a citizen of the United States, and a resident of Chicago, in the county of Cook and State of Illinois, have invented certain new and useful Improvements in Coil Structures for Transformers and the like; and I do hereby declare that the following is a full, clear, and exact description thereof, reference being had to the accompanying drawings, and to the characters of reference marked thereon, which form a part of this specification.

This invention relates to a novel winding coil structure of the pancake or disk type, and is adapted more especially to that type of winding coil which is made up of a spirally wound flat wire, such, for instance, as is shown in my prior application for U. S. Letters Patent Serial No. 39,044, filed July 10, 1915, of which the application is a division.

Among the objects of the present invention is to mechanically strengthen the units or coils so that they may be individually handled without danger of collapsing them and to strengthen them in the assembled transformers or other electro-magnetic devices.

30 A further object of the invention is to provide, in connection with a winding unit which is thus made up of flat bare wires with the turns insulated by one or more strips of insulating material, means whereby the thin flat wires may be joined to relatively heavier wires or conductors at the inner side of the coil which relatively heavier wires are provided in order to mechanically strengthen the coil structure.

40 Another object of the invention is to provide a novel means of uniting the innermost turn of the coil in such a way as to produce a stiff mechanical union and to insulate one end of the turn from the other end thereof.

45 Other objects of the invention are to improve and simplify coil structures of this character, and the invention consists in the combination and arrangement of the parts shown in the drawings and described in the specification, and is pointed out in the appended claims.

In the drawings:—

Figure 1 is a face view of a winding coil or unit embodying my invention.

Fig. 2 is a section on the line 2—2 of 55 Fig. 1.

Fig. 3 is a detail of the insulating joint between the ends of the inner stiffening turn shown in Fig. 1.

As shown in said drawings, the coil 10 is 60 made up principally of a spirally wound flat wire comprising a plurality of turns 11 that are spaced by suitable insulating material 12, such, for instance, as one or more sheets of paper.

65 In order to stiffen the coil structure, the inner and outer turns 14, 15, respectively, are made of relatively heavier wire, the inner turn 14 being of relatively larger cross section than the outer turn and sufficiently 70 massive to afford the desired rigidity at the inner side of the coil structure. As herein shown the innermost turn 14 consists of a half round cross section with the flattened side thereof lying against and in metal to 75 metal contact with the next adjacent flat turn. The first few turns 16 of the conductors are preferably made thicker than the turns 11 which make up the principal part of the coil structure, and by reason of the 80 small potential difference between said turns, the insulation 17 need not be so great as between the turns toward the outer side of the coil.

The flat thin wire which constitutes the 85 principal portion of the coil structure is preferably joined to the heavier wire 16 by means not requiring solder, it not being practicable to solder the thin wire.

The present method is best shown in Fig. 90 2, and it consists, at the inner part of the unit, of laying on the flat face of the outer heavier turn 16, and for a substantial length therealong and in metal to metal contact with the outer turn 16 the innermost end 95 of the thin flat wire 11 which composes the main body of said unit. The thin and thicker flat wire in metal to metal contact produce a reliable electrical contact without other fastening means; the inner stiffening 100 connecting turns being held assembled by pressure due to the winding of the wire.

The inner turn 14 may be fastened together at its ends by means of an insulating dowel 18 the ends of which enter sockets 105 formed in the ends of the inner turn, and said dowel is provided between its ends with a flange 19, which bears against the flat

ends of the inner turn to prevent short circuiting about the inner turn. The said flanged dowel also provides an amply rigid connection between the ends of the inner 5 turn.

The outer stiffening turn is made of such thickness that it acts by its own resiliency to hold the thinner wire of the coil structure from unwinding.

10 I claim as my invention:—

1. A winding unit composed of a spirally wound, flat wire with an insulating medium between the turns thereof, the inner and outer turns of the unit being of large cross 15 section to mechanically stiffen the unit.

2. A winding unit composed of a spirally wound, flat wire with an insulating medium between the turns thereof, the inner turn of the unit comprising a stiff wire to brace 20 the winding and means for electrically connecting the inner turn of thin wire of the unit to the bracing turn comprising a few turns of flat wire of intermediate thickness, with the turns insulated from each other 25 laid at one end against the stiffening turn in metal-to-metal contact and laid at the other end thereof in metal-to-metal contact against the inner end of the thinner wire of the winding.

30 3. A winding unit composed of a spirally wound flat wire with an insulating medium between the turns thereof, the inner turn of the unit being of large cross section to mechanically stiffen the unit, and electrically connected to the thin wire, and an insulat- 35

ing and connecting device between the ends of the said inner turn.

4. A winding unit composed of a spirally wound flat wire with an insulating medium between the turns thereof, the inner turn of 40 the unit being of large cross section to mechanically stiffen the unit, and electrically connected to the thin wire, the ends of said inner turn being provided with openings and a dowel seated in said openings to 45 mechanically connect the said ends and provided with an insulating barrier to electrically insulate said ends from each other.

5. A winding unit composed of a spirally wound flat wire with an insulating medium 50 between the turns thereof, the inner turn of the unit being of large cross section to mechanically stiffen the unit.

6. A winding unit composed of a spirally wound flat thin wire, with an insulating medium between the turns thereof, the outer turn of the winding comprising a wire including somewhat less than a complete circle and of a cross section and stiffness to mechanically brace the winding and prevent 60 unwinding of the thinner turns.

In witness whereof I claim the foregoing as my invention, I hereunto append my signature in the presence of two witnesses at Chicago, Illinois, this 19th day of March, 65 1917.

CHESTER H. THORDARSON.
